UNITED STATES PATENT OFFICE.

HARRY T. SHEARER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

CAM-GRINDER ATTACHMENT FOR GRINDING-MACHINES.

1,156,323.

Specification of Letters Patent. Patented Oct. 12, 1915.

Application filed December 19, 1910, Serial No. 588,226. Renewed August 26, 1915. Serial No. 47,485.

To all whom it may concern:

Be it known that I, HARRY T. SHEARER, a citizen of the United States, residing at Waynesboro, in the county of Franklin and State of Pennsylvania, have invented certain new and useful Improvements in Cam-Grinder Attachments for Grinding-Machines, of which the following is a specification.

10 My said invention consists in various improvements in the details of construction and arrangement of parts of cam grinding attachments for grinding machines, whereby such a machine of a common type, as 15 for example, a "Landis" grinding machine, may be readily adapted for grinding cams of various dimensions without materially modifying the arrangement or operation of the main parts of the machine, all as 20 will be hereinafter more fully described and claimed.

Referring to the accompanying drawings which are made a part hereof and on which similar reference characters indicate similar 25 parts, Figure 1 is an end elevation of an attachment of my improved construction in the position it occupies on the machine, ready for use, Fig. 2 a view partly in front elevation and partly in section of one of 30 said attachments, and Fig. 3 a detail section on the dotted line 3—3 in Fig. 1.

In said drawings the portions marked A represent the work-table of the grinding machine, B the support for the grinding 35 wheel attachment and C the pivoted frame supporting the bearings carrying the mandrel.

The work-table A may be the work-table of any grinding machine of appropriate 40 construction, such as the well known "Landis" type above referred to.

The support B is a casting preferably in the form of a hollow shell adapted to support and inclose the main portions of the 45 cam grinding attachment. It is formed with a flange b on its lower rear edge adapted to engage with the rear edge of table A and with projecting lugs on its lower rear corners having notches with which the 50 clamping bolts a engage. Said clamping bolts a are mounted with their heads in a longitudinal T-slot in the table A, in the well known manner, and are provided with nuts a' by which said support may be 55 securely clamped in any position desired.

throughout the length of the table. Said support B is of a suitable length to accommodate the other parts of the attachment and at its upper end is provided with bearings for the pivot of the hinged frame C 60 and is formed with elongated openings b in its ends in which the work carrying shaft or mandrel may swing.

The frame C comprises a casting having a cylindrical part C' at its upper end in 65 which a pivot shaft c is secured by set-screws c'. The ends of said pivot-shaft project beyond the ends of said frame and are journaled in bearings in the upper end of frame B. By this means said frame is 70 mounted to swing transversely of the table A and toward and from the grinding wheel (not shown). The lower end of said frame carries another cylindrical part C² in which are formed bearings for the work and pattern carrying mandrel C³. Said bearings are provided with bronze, or other suitable, bushings and mandrel C³ is mounted therein. At the ends of said frame are formed tubular parts c⁸ containing channels leading from just beneath oil cups c⁴ in the top of support B to said bearings to provide for their lubrication. Said mandrel has a collar C⁴ on its outer end and sleeve C⁵ secured between said collar and pattern 80 P on which is formed a crank-arm c⁶ adapted to be connected by a sliding connection to a crank-pin c⁸ on a driving wheel C⁶ for driving said mandrel and permit it to swing with frame C during the operation. The 85 pattern, or master-cam, P, is mounted near one end of said mandrel and keyed thereto and near its opposite end the cam to be ground is also keyed thereon. A shoe C⁷ is mounted in a support S in line with the 90 master-cam P. Said support S is secured to a projecting arm B² of the support B by means of a clamping bolt c⁷, the head of which engages with a T or flanged groove in said arm B², as shown most clearly in 95 Fig. 3. It is supported in proper relative position to the master-cam by means of said clamping screw c⁷ and an adjusting screw c⁸. The shoe C⁷ is clamped in its seat between appropriate jaws of said support S by means of clamping screws s. The parts are inclosed by a cover C⁸ which is held in position by a screw c⁹, which passes through said cover and into a screw-threaded 100 perforation in the end of arm B². A nut x 105

110

is mounted on said screw to prevent the same from becoming separated from said cover C² when the same is removed from position, as when the parts are adjusted. 5 Said shoes are formed on the arc of a circle substantially corresponding to the circle of the grinding wheel and are furnished in sets of a number equal to the number of inches wear for which the grinding wheel 10 is adapted, so that as the grinding wheel is worn down inch by inch the shoes are changed to correspond. The shoe when put in place is the arc of a circle the diameter of which is one-half inch less than the diameter of the grinding wheel and said shoe 15 is used until the diameter of said grinding wheel is worn to one-half inch less than the diameter of the circle of which the surface of the shoe is an arc. By this means the master-cam is supported against that portion of the shoe which substantially corresponds at all times in shape or curvature with the shape or curvature of the portion of the grinding wheel which is operating upon the work and the work is thus ground true to its pattern. Immediately beneath the master-cam P I mount an oil pan 10 having an opening through its top through which the periphery of the master-cam may project. In said pan I mount a follower 11 on springs 12 and on top of said follower a quantity of waste, or other absorbent material, 13, which serves to take up the oil with which the oil pan is filled 20 and against which the periphery of the master-cam contacts when turned to bring its widest point to the position shown in Fig. 1. Thus at each revolution of the master-cam its apex wipes against the surface of said oil saturated absorbent material and picks up sufficient of the lubricant to keep the contact surfaces of shoe C² and master-cam P thoroughly lubricated at all times and thus obviate any undue wear between 25 said shoe and the master-cam.

On the lower side of one end of part C² is formed a lug 15 with which the nose 16 of a spring mounted push-rod 17 engages. Said push-rod is mounted to slide in a bearing in lug 18 on support B and a coiled spring 19 surrounds said push-rod and being interposed between its nose 16 and the seat within said bearings, the action of said spring will normally hold the swinging bearing C with the mandrel C³ and master-cam P against shoe C² at all times.

The operation is as follows: The various parts being in the position shown in the drawings, the attachment is placed upon the 60 grinding machine, the support B being secured on the work-table A as indicated in Fig. 1. The pattern, or master cam, P, is keyed in position on the appropriate end of the mandrel C³ and the cam to be ground, or 65 work, W is keyed to the opposite end of said

mandrel, as shown in Fig. 2. The grinding wheel of the machine (indicated by dotted lines in Fig. 1) is brought into position to operate upon the face of the work and the mandrel C³ connected with the gearing for 70 driving the same. As said mandrel revolves, the master-cam bears upon shoe C² and thus operates to swing the frame C, carrying the mandrel C³ and the work W, on its pivots to maintain the work in the same 75 relation to the grinding wheel as the pattern maintains to said shoe. The spring 19 operates to maintain the pattern in close contact with the shoe at all times while permitting the free swinging motion of the 80 frame carrying the work. By this means the work is ground to the form of the pattern automatically and when so ground, or when the grinding wheel is in contact with the work throughout the entire revolution of 85 said work, across its entire face, said work may be removed and another cam put in position to be ground. The pattern P is changed from time to time and other patterns substituted corresponding with the 90 form of the work to be ground. Said patterns are furnished in sets of standard sizes and when special forms of cams are to be ground the pattern therefor may be made by the original pattern, cut of suitable material 95 in the usual manner, as will be readily understood.

Having thus fully described my said invention, what I claim as new and desire to secure by Letters Patent, is:

1. A cam grinding attachment for grinding machines comprising suitable supports mounted on the work table of the machine, a swinging frame mounted on said supports, a mandrel mounted in bearings in said frame, means for driving said mandrel, a pattern corresponding in shape to the work to be ground mounted on said mandrel, a stationary shoe mounted in line with said pattern with its face adapted to contact with the periphery of said pattern and formed with its bearing surface of a curvature corresponding substantially to the curvature of the grinding wheel, means on said mandrel for securing the work to be ground in line with said pattern, and means for holding said pattern yieldingly in contact with said shoe, substantially as set forth.

2. A cam grinder attachment for grinding machines comprising a support formed to inclose the working parts of said attachment and mounted upon the work-table of the machine, a swinging frame mounted on a pivot journaled in the upper end of said support, said frame being formed with bearings in its lower end, a mandrel journaled in said bearings and extending through slots in the ends of said supports, means for driving said mandrel, a pattern mounted on one of the projecting ends of said mandrel, the

work mounted on the other end of said mandrel, and a stationary shoe mounted in line with the said pattern and adapted to serve as a bearing therefor during the operation, 5 substantially as set forth.

3. A cam grinder attachment for grinding machines comprising a support mounted on the work-table of the machine, a frame pivoted in said support, a mandrel journaled 10 in bearings in said frame, a pattern mounted on said mandrel, means for driving said mandrel, a stationary rest for said pattern, a lubricant container mounted beneath said

pattern and formed with an opening through which a part of said pattern is adapted to 15 project at each revolution thereof, and the work also mounted on said mandrel, substantially as set forth.

In witness whereof, I, have hereunto set my hand and seal at Waynesboro, Pennsylvania, this 28th day of November, A. D. nineteen hundred and ten.

HARRY T. SHEARER. [L. S.]
